COMBINED PHOTOGRAPHIC ENLARGER AND COLOR ANALYZER

Masakazu Nakanishi, Hashimoto, Yoshiharu Hyodo,
Aichi, and Haruki Yamaguchi, Toyokawa, Japan, as-
signors to Minolta Camera Kabushiki Kaisha, Osaka,
Japan

Filed Jan. 17, 1974, Ser. No. 434,309

Claims priority, application Japan July 18, 1973

Term of patent 14 years

Int. Cl. D16—03

U.S. Cl. D61—1 Q

FIG. 1 is a front elevational view of a combined photographic enlarger and color analyzer embodying our new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof.

We claim:

The design for a combined photographic enlarger and color analyzer, as shown.
